UNITED STATES PATENT OFFICE

EDWIN E. BARNEY, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,230,094.

Specification of Letters Patent. Patented June 19, 1917.

Application filed January 15, 1915. Serial No. 2,351.

To all whom it may concern:

Be it known that I, EDWIN E. BARNEY, citizen of the United States, and resident of Ilion, in the county of Herkimer and State of New York, have invented certain new and useful Improvements in Type-Writing Machines, of which the following is a specification.

My present invention relates to ribbon mechanism for typewriting machines and its general object is to provide improved mechanism of the character specified. More particularly one object of the invention is to provide new and improved means for varying the vibratory movement of the ribbon so that different widthwise portions or color fields may be employed at will; another object is to provide new and improved ribbon stop devices; and a still further object is to provide novel devices for dispensing entirely with the use of the ribbon so as to facilitate, for example, the writing of stencils.

To the above and other ends my invention consists in the features of construction, combinations of devices and arrangements of parts hereinafter described and particularly pointed out in the claims.

In the accompanying drawings,

Figure 1 is a vertical longitudinal sectional view of a No. 10 Remington front-strike typewriting machine embodying my invention in its preferred form, parts of the machine being omitted and parts broken away.

Fig. 2 is a face view showing ribbon indicating devices and a finger button or hand piece by which the ribbon vibrating and stop mechanisms are varied and controlled.

Fig. 3 is a transverse vertical sectional view taken on a plane indicated by the dotted line $x-x$ in Fig. 1 and looking forward.

Fig. 4 is a perspective view of the ribbon vibrating and stop mechanisms and certain of the devices for controlling them.

Fig. 5 is a fragmentary rear elevation of some of the mechanism shown in Fig. 4 but with the parts shifted for upper case writing.

Fig. 6 is a fragmentary enlarged sectional view corresponding to Fig. 1.

Fig. 7 is a sectional view of a detail.

Figs. 8, 9 and 10 are transverse sectional views taken on planes indicated by the dotted line $y-y$ in Fig. 5 and looking down-

ward, the views showing the parts in the different relationships in which they may be set.

As appears from Figs. 1 and 3 the main frame of the machine comprises a base 1, 60 posts 2 and a top plate 3 which support fixed guide rails 4, said rails co-operating through anti-friction balls 5 with a carriage truck 6. A platen 7 is mounted in a platen frame 8 which is shiftable connected with the truck 6 by devices 9 so that said platen frame may be moved up and down to shift the platen and thereby change case. Said platen frame comprises a cross bar 10 on which is journaled a roller 11 that is adapted to run on a shift rail 12 supported by upright arms 13 rising from a transverse bar 14 which in turn is supported on upright arms 15, each arm 15 being pivoted at its lower end at 16 to a lever 17 provided with a shift key 18. 75 The platen normally stands in lower case position but may be raised or shifted to upper case position by depressing either of the shift keys 18 which thus control the shifting movements of the platen through the shift 80 frame comprising the rail 12, cross bar 14 and pairs of arms 13 and 15. Printing key levers 19 are provided with keys 20 and are connected by links 21 with sub-levers 22, said sub-levers in turn being connected by 85 links 23 with front-strike type bars 24 mounted on hangers 25 secured to a stationary segment or support 26. A universal bar 27 underlies the key levers and is supported on arms 28 depending from crank 90 arms 29 which project rearward from a transverse rock shaft 30 having end pivots supported in the sides of the base. Projecting from said rock shaft near its middle is an arm 31 which is connected by a link 32 95 with certain escapement devices (not shown) but which are preferably of the usual construction.

Ribbon spools 33 are supported, one at each side of the machine, above the top plate 100 on shafts 34 and a ribbon 35 is wound on said spools and fed upward therefrom through openings 36 in the top plate, thence over stationary guides 37 and through a ribbon vibrator, hereinafter described, arranged 105 centrally between said guides. Means for turning the ribbon spools in alternation to feed the ribbon longitudinally back and forth operate on the shafts 34, which shafts bear in lugs 38 depending from 110

the top plate and extend fore and aft of the machine. The ribbon spools are supported on the front ends of these shafts while their rear ends carry beveled pinions 39 which are adapted to mesh with beveled pinions 40 mounted on a ribbon driving shaft 41 bearing in stationary lugs 42, one pinion 40 being disposed near each end of said shaft. The driving shaft is connected 5 through intermeshing beveled pinions 43 and 44 with a spring drum 45 in such a way that when the carriage comprising the truck 6 and platen frame 8 is drawn leftward under the pull of the spring drum with 10 which it is connected by a band 46, the shaft 41 will be turned, causing a turning of one or the other of the ribbon spools and consequent longitudinal feeding of the ribbon. Means preferably of the ordinary Remington 15 ton construction are provided for moving the driving shaft 41 back and forth endwise to cause an alternate engagement of the pinions 39 by their associate driving pinions 40 to reverse the direction of the 20 ribbon feed.

The ribbon carrier or vibrator comprises, as best appears from Figs. 4, 5 and 6, a body portion 47 of sheet metal from which depends a narrow integral stem portion 48. The sides of the body portion are curled or rolled, as indicated at 49, to provide tube-like portions which receive upstanding wires 50, the upper ends whereof are bent to provide guide loops 51 through which the ribbon is threaded. The wires 50 are frictionally held in the tube-like portions 49, the construction being such that the wires may be readily adjusted up and down on the body portion so as to properly locate the guide loops 51 and the printing portion of the ribbon which extends between them. The construction provides a vibrator which is simple and inexpensive, is light in weight, and affords a ready relative adjustment between the body and stem on the one hand and the head comprising the wires 50 on the other. The stem 48 at its lower end is curled around and pivotally supported by a pivot pin 52 which is mounted on the forward end of a horizontally disposed arm 53 comprised in a ribbon operating member or lever frame 54, said frame further including laterally diverging branches 55 and a central downwardly extending arm 56 terminating in a rolled or cylindrical end portion 57. The branches 55 are curled around and frictionally hold a pivot pin 58 which is pivotally supported on a guide frame which is designated as a whole by the numeral 59. Said guide frame comprises two parallel side arms 60 connected at the top and bottom by integral cross bars numbered respectively 61 and 62. Extending upward from the cross bar 62 are lugs 63 which are inclined rearward behind the rail 12 and

receive screws 64 by which the guide frame 59 is fixed to said rail. The ends or sides of the cross bar 62 terminate in rearwardly bent ears 62^a which are formed with bearing openings in which the projecting ends of the pivot rod 58 are journaled. The arms 60 incline upward and forward in front of the rail 12 so that the cross bar 61 is at the front side of the platen. Said cross bar near its ends is curved forward laterally 75 and terminates in upstanding guide fingers 65 behind which the ribbon passes before it reaches the vibrator, said fingers providing a guide for the ribbon in the vicinity of the vibrator and which remains stationary during vibratory movements of the vibrator and lever. Depending centrally from the cross bar 61 is a lug 66 which provides a support for a headed shoulder screw 67, said screw extending through an elongated vertical slot 68 cut in the body 47 of the vibrator. The sides 68 of the slot are formed by bending back the metal from the slot opening so as to provide smooth and comparatively wide surfaces for coöperation 85 with the sides of the guide screw 67. It will be observed that the guide frame 59 which is supported on the platen shifting frame and shifts with the platen combines several functions, as it provides a pivotal 95 support for the operating lever, a guide for the vibrator and also guides for the portions of the ribbon which extend from the vibrator to the spools or more directly to the stationary guides 37.

The operating lever and vibrator are adapted to be actuated by an actuator or lever member which is mounted to shift automatically when the platen, the vibrator and the operating lever are shifted, but to a less extent than these three elements. In other words, the actuator receives a differential shift. The purpose of this, as will more clearly appear from what follows, is to compensate as between the operating lever which shifts with the platen and the element from which the actuator itself receives motion and which does not shift at all. The actuator or sub-lever, designated as a whole by the numeral 69, is vertically disposed behind the shift bar 14 and is preferably formed of sheet metal, its upper end portion providing a comparatively broad face 69^a for coöperation with the round end 57 of the operating lever. The lower end or arm of the sub-lever has a lateral slot 70 below which the metal is bent or shaped, so as to provide at the left-hand side a step or face 71 which is behind the surface or face 72 at the right-hand side, said face 72 being in the general plane of the sub-lever. The two faces are adapted to coöperate separately with the rounded upper end of a key controlled operating finger or device 73 which as clearly shown in Fig. 1, rises from the 130

crank arm 31 to which it is fixed as by rivets 74. The sub-lever 69 is of the first order, being pivoted between its ends. For this purpose about midway of its length it is 5 provided at its side edges with rearwardly bent, perforated ears 75 which receive and bear rotatably on a pivot pin 76. This pivot pin is supported on a bracket, bearing member or slide, designated as a whole by the 10 numeral 77, best shown in Figs. 4 to 7. Said member 77 comprises a horizontally disposed body portion or slide bar proper 78 from the middle of which rises an upright portion 79 terminating at the top in a forwardly bent slotted lip 80 which receives the upper end of a guide finger 81 that is screwed or otherwise secured to the top of the bar 14. This guide finger serves as well 15 to support the slide 77 and prevent it from pulling away toward the rear through gravity. The portion 79 is provided at its sides with rearwardly bent parallel ears 82 which loosely embrace the ears 75 and support the ends of the pivot pin 76 which project beyond 20 said ears 75. The body portion 78 is provided near its ends with horizontal slots 83 which receive headed supporting and guiding screws 84, said screws being threaded into links or arms 85 about midway of 25 their lengths. Each link 85 is pivotally supported at its inner end on a shoulder screw 86 which is threaded into the rear of the shift bar 14, the two screws 86 being close together and behind the middle portion 30 of the slide. The outer ends of the links 85 are pivotally anchored at 87 to stationary supports or angular brackets 88 suitably secured to the under side of the top plate and inclining forward and downward 35 therefrom. It will be understood that the outer ends of the links 85 have fixed pivots as distinguished from their inner ends which have shiftable pivots, being supported on the platen shifting frame. The 40 screws or supports 84 are fixed or supported at such points on the links 85 as to receive half the amount of shifting movement which the platen shifting frame comprising the shiftable bar 14 receives when one of 45 the keys 18 is depressed. Consequently the slide 77 which is mounted or supported on these screws 84 will, together with the sub-lever 69, be shifted differentially or to half the extent that the platen, together with the 50 ribbon vibrator and operating lever, is shifted. In other words, when the operating lever 54 is shifted the full extent of the platen shift the sub-lever 69 which operates on said operating lever will be shifted only 55 half as far and as a result of this the length of the load arm of the lever or the distance from the pivot 76 to the point of engagement with the lever end 57 will be increased. However, the length of the power arm or the distance 60 from the pivot 76 to the point of engagement with the finger 73 will at the same time be correspondingly increased so that there will be no variation, as a result of the shift, in the movement transmitted from the device or actuator 73 to the operating lever 75 65 through the sub-lever 69. In other words, since the finger 73 has a constant movement communicated to it from the action of the printing keys on the universal bar, the operating lever 54 and ribbon vibrator will receive a corresponding constant throw or extent of movement in spite of the fact that the vibrator and operating lever shift to change case while the actuator 73 is non-shifting. This result is due to the fact that 70 the device or element 69 which is interposed between the operating fingers 73 and the lever 54 and transmits movement from one to the other has a differential or compensatory shifting movement as contrasted on 75 the one hand with the lever 54 which has a greater shifting movement and on the other hand with the finger or lever arm 73 which has no shifting movement. In lower case the links 85 incline downward from 80 their pivots 87 so that they are at an angle below the horizontal lines adjoining said pivots. As a result, however, of the upward shifting movement the links will be swung up until they are at an equal angle above 85 the horizontal line. 90

The slide 77 is so mounted that it may not only be shifted up and down with the platen but may also be shifted sidewise at right angles to this movement so as to move 95 the sub-lever back and forth from side to side and bring either one of the steps 71 or 72 opposite the finger 73 for the purpose of varying the ribbon throw and changing the ribbon fields. Also a further lateral 100 movement may be communicated to the slide and sub-lever in order to carry the latter completely out of the field of operation of the finger 73. The means for thus laterally shifting the slide and sub-lever 105 extend to the front of the machine and comprise, as shown in Figs. 1 to 4, a link or bar 89 which is pivotally connected at its inner end at 90 to a lug 78a rising from the left-hand end of the slide bar 78. The 110 outer end of the link 89 is pivotally connected at 91 to a crank arm 92 rising from and fixed to the rear end portion of a rock shaft 93 that extends fore and aft of the machine at its left-hand side. The rear end portion of said rock shaft bears in an angular bracket 94 secured by screws 95 to the under side of the segment 26, while the forward end portion of said rock shaft 93 bears in a plate 96 secured by screws 97 to the left-hand front post 2. Forward of said plate, the rock shaft is provided with a knurled button or finger piece 98. Behind the finger piece a pointer 99 projects radially from the rock shaft and cooperates with indicat- 115 120 125 130

ing marks or devices 100 on the plate 96. The middle mark 100 corresponds to the upper field of the ribbon 35 which, in the present instance, is preferably a bi-color 5 ribbon, the upper stripe or field *a* being black and the lower field *b* being red. When the pointer 99 is brought opposite the lowermost indicating mark as in Fig. 2 the shaft 93 will be turned so that the 10 slide 77 and the sub-lever carried by it will be drawn to the position shown in Figs. 3, 5 and 8 with the forward step 72 opposite the finger 73. The slide and sub-lever, together with the connected parts in- 15 cluding the rock shaft 93, will be maintained set in this position by detent devices comprising a lug or rounded projection 101 on the rear face of the bracket 94. This projection is adapted to coöper- 20 ate in turn with three holes or openings 102 formed in a spring detent plate 103 screwed or otherwise fixed to the rock shaft 93 behind the bracket 94. In the present instance the right-hand hole 102 is engaged 25 with the lug 101, thus fixing the rock shaft and through the crank 92 and link 89 setting the slide and the sub-lever in a pre-determined position laterally of the finger 73 and the operating lever 54. With the 30 parts thus arranged, an actuation of one of the printing keys 20 will operate through the universal bar and connections to swing the finger 73 rearward. Normally the finger is slightly separated from the operating 35 face 72 as shown in Figs. 1 and 6 so that there is a slight lost motion before the finger picks up said lever and swings it on its pivot, causing the upper arm of the sub-lever acting on the operating lever to lift 40 the vibrator and move it upward to interpose the ribbon in the path of the operated type bar. The parts are so proportioned and arranged that this upward movement will carry the ribbon far enough to 45 present the lower field *b* to the types; and so long as the parts remain set as described this throw of the ribbon will be constant for each actuation of a printing key with the result that the type impressions will fol- 50 low a straight path along and centrally of the ribbon field *b*. It will be understood that the shifting of the platen to upper case position and the consequent shifting of the parts, as illustrated in Fig. 5, will not affect 55 the extent of ribbon throw which will be the same as in lower case position. The ribbon vibrator will be shifted upward with the platen and to the same extent, so that the normal relationship between the vi- 60 brator and the platen will be the same in upper case as in lower case position.

When it is desired to use the upper field *a* of the ribbon 35 the rock shaft 93 is turned through the finger button 98 until 65 the pointer 99 is brought opposite the mid-

dle indicating mark 100. The turning movement of the rock shaft acting through the crank arm 92 and the link 89 will shift the slide 77 laterally toward the right. As a result the sub-lever 69 will be shifted 70 rightward until the operating face 71 at its lower end will be brought opposite the finger 73, as shown in Fig. 9. The face 71, it will be noted, is in a vertical plane somewhat behind or in rear of the face 72 75 so that as a consequence of the resetting the initial lost motion between the finger 73 and the sub-lever will be increased, resulting in less movement being communicated to the sub-lever from said finger. The 80 face of the upper end 69^a of said sub-lever is in a single vertical plane throughout its width so that its fore and aft relationship with the operating lever 54 will not be affected by the lateral shift. The ribbon 85 throw changing devices will be maintained set in their new positions by the detent devices 101 and 103, the lug or detent 101 being at this time engaged with the middle hold in the detent plate 103. With the 90 parts thus set an actuation of a printing key, acting through the finger 73, will as stated, communicate less movement to the sub-lever, and as a consequence less motion will be communicated to the operating lever 95 and vibrator. The parts are so proportioned and adjusted that this movement will raise the vibrator and throw the ribbon far enough to bring the upper field *a* opposite the printing point and into the path of the 100 operated type bar. Since the throw will be constant as long as the parts are maintained thus set and whether the platen is in lower or upper case position the type impressions will follow a straight path 105 lengthwise of the field *a* and about centrally thereof.

Should it be desired to dispense entirely with the use of the ribbon when the type bars are actuated, for the purpose of writing stencil sheets or for any other desired purpose, the finger button 98 is turned to bring the pointer 99 opposite the uppermost indicating mark 100, this resulting in a turning of the rock shaft and a consequent setting thereof with the detent 101 engaged with the left-hand detent hole 102. As a consequence the slide 77 will be moved to its extreme right-hand position and the sub-lever 69 will be carried rightward past the 110 finger 73 and set as shown in Fig. 10, so that at printing operations the finger will move idly without affecting the sub-lever or ribbon vibrator, these remaining quiescent and maintaining the ribbon below the printing 115 point.

In order to limit positively both the up and the down movements of the ribbon carrier or vibrator when it is vibrated during printing operations, stop devices are pro- 120 130

vided which, in the present instance, are connected to be shifted and set automatically with the sub-lever 69 to vary the stop devices in correspondence with the variation 5 of the throw imparted by the sub-lever. Said stop devices are also mounted to shift with the platen so that their relationship with the ribbon vibrator will not be changed or affected when the platen is shifted. The 10 stop devices, as best appears from Figs. 4 to 7, comprise a stop-supporting frame or member designated as a whole by the numeral 104 and comprising a right angled body portion 105 which embraces the front 15 and under sides of the shift bar 14 and is slidably mounted on said shift bar by headed screws 106 which pass through elongated slots 107 formed in the front wall of said body portion and are threaded into the front 20 of said bar 14. Between the under side of the part 105 and the bottom face of the bar 14 is interposed a flat friction spring 108 (Fig. 7), the ends of which are bent downward and take into holes in the under side 25 of the part 105. There may also be provided a leaf spring 109 secured as by screws to the under face of the bar 14 and having its free end pressing upward against the under part of the body 105. Connection between the 30 supporting frame 104 and the slide 77 is provided by means of an angular finger 110 which extends upward and is then bent rearward from the right-hand end portion of the body 105, as best shown in Fig. 4, said finger 35 engaging loosely in a vertical slot 111 cut in a lug 112 rising from the right-hand end of the slide bar 78. The connection is such that the frame 104 is compelled automatically to slide lengthwise of the bar 14 when- 40 ever the slide 77 is shifted laterally but the frame 104 and the slide 77 may be shifted up and down differentially when the platen is shifted, the frame 104 participating in the full extent of the platen shift while the 45 slide 77 is shifted to a less extent. Rising about centrally from the body portion 105 is an integral arm 113 which is bent or offset forward, said arm providing a support for the stop device proper 114. Said stop 50 device is adjustably secured to the arm 113 by pivot screws 115 which are threaded into the arm and pass through elongated vertical slots 116 in the upright body portion of the device 114, thus permitting fine up and 55 down adjustments of the device 114 in assembling the mechanism. From the body portion of the device 114 extend leftward two stop arms 117 and 118. The lower arm 117 is provided at its outer end with a 60 depressed portion 119 while the upper arm terminates in a lug 120 which projects downward just to the right of the depressed end 119. The arms 53 of the operating lever 65 extends forward between these two arms 117 and 118, said arms providing stops for posi- tively arresting the operating lever and vibrator in both directions of their movements. Normally the operating lever engages with the arm 117 which limits its downward movement and also maintains it in proper 70 normal relationship with the platen when the latter is in lower case position, and also supports and raises the operating lever and vibrator when the platen is shifted to upper case position. Preferably a spring tongue 75 121 is suitably secured to the under face of the arm 53 and is interposed at its free end between said arm and the stop arm 117 to act as a cushion between the parts and to eliminate noise. When the sub-lever is set 80 as in Fig. 3 to give the vibrator its greatest throw, the bottom edge of the stop arm 118 underlies the arm 53 which will contact with it at the end of the throw so as to insure the arrest of the printing portion of the 85 ribbon with the field *b* opposite the printing point. When the sub-lever is shifted to give the short throw of the ribbon, the stop device 114 is correspondingly shifted to bring the lug 120 over the arm 53, this 90 lug being adapted to arrest the operating lever and vibrator at the completion of the short throw of the ribbon with the upper field *a* opposite the printing point. It will 95 be observed that while the stops for arrest- 100 ing the printing movement of the vibrator are in different horizontal planes, one above the other, the stop arm 117 is in the same horizontal plane for both these throws, so that the normal position of the operating lever and vibrator is unaltered by the throw changing operation. However, when the sub-lever is shifted to the Fig. 10 position to provide for mimeographing, the stop de- 105 vice 114 will be automatically moved right- 110 ward far enough to bring the lower step 119 under the arm 53 which will drop downward by gravity to this lower position, carrying with it the ribbon vibrator and ribbon. The consequence is that when mimeographing, the printing portion of the ribbon is slightly lower than it is ordinarily the result being that sufficient clearance is insured for the types when they are thrown to the printing point and they are thus pre- 115 vented from accidentally catching on the upper edge of the ribbon during mimeographing or stencil writing operations. The edge 122 joining the lower step 119 with the arm 117 is inclined downward toward the 120 left so that in moving the stop device toward the left and resetting the sub-lever in the Fig. 8 or Fig. 9 position, the inclined edge 122 acts as a cam and causes the lever arm 53 to ride up on to the arm 117. It will 125 be understood that during the automatic adjustments of the stop devices the parts 104 and 114 move as a single or unitary member. It will be observed that by my present 130 invention there is provided in combination

a ribbon vibrator, an operating lever, devices for actuating the operating lever comprising a second or sub-lever, and means for effecting a relative shift between the 5 two levers in order to vary the throw of the operating lever, such relative shift being brought about in the present instance by shifting the sub-lever laterally or transversely of the operating lever through 10 means extending to the front of the machine and terminating in a finger piece or button, as 98; that said sub-lever is upright and is slidable laterally and settable in predetermined positions to vary its effect 15 on the operating lever and is also settable in a position where it is ineffective on the operating lever; that the ribbon vibrator and certain of its actuating devices, in the present instance the sub-lever, are differentially shiftable automatically when the case 20 shifting mechanism is operated to effect a relative shift between the platen and the types, caused, in the present instance, by shifting the platen; that as a result of such 25 automatic shift the normal positions of both the vibrator and the sub-lever are changed; that this shifting movement of the sub-lever is distinct from and independent of its movements during printing operations; 30 that the shifting movement of the sub-lever is different in extent from that of the vibrator, being substantially half that of the vibrator; that the sub-lever is an actuating device which is intermediate the shiftable 35 ribbon vibrator and a non-shiftable key-operated actuating device, viz., the finger 73; that the sub-lever is pivoted on a bracket which has a pin and slot connection with each of two links at points about midway 40 of the lengths of the links, this construction affording a shifting up and down movement of the sub-lever simultaneously with the links and vibrator and also permitting a lateral sliding movement of the sub- 45 lever and its bracket, independently both of the links and the shiftable platen; and that ribbon stop devices are provided including variable stops to limit variable movement of the ribbon toward the printing point as well as to vary its point of 50 arrest during movement in the opposite direction.

What I claim as new and desire to secure by Letters Patent, is:—

55 1. In a typewriting machine, the combination of a ribbon vibrator, a bell crank operating lever, an upright lever for actuating said operating lever, printing keys operative on said upright lever, and means 60 extending to the front of the machine for varying the effect of said printing keys on said bell crank operating lever, said means comprising devices for shifting said upright lever laterally.

65 2. In a typewriting machine, the combi-

nation of a ribbon vibrator, an operating lever, a slidably mounted upright lever member for actuating said operating lever, printing keys operative on said lever member, and means controlled by a finger piece at the 70 front of the machine for varying the effect of said printing keys on said operating lever and altering the throw of the ribbon, said means comprising devices for sliding said lever member laterally and setting it 75 in predetermined positions.

3. In a typewriting machine, the combination of a ribbon vibrator, an operating lever, a slidably mounted upright lever member of the first order, the upper arm 80 of said lever member being effective to actuate said operating lever, printing keys operative on the lower arm of said lever member, and means controlled by a finger piece at the front of the machine to vary the 85 extent of movement communicated to said operating lever when said printing keys are actuated, said means comprising devices for sliding said lever member laterally and setting it in predetermined positions. 90

4. In a typewriting machine, the combination of a ribbon vibrator, an operating lever, an upright lever for actuating said operating lever, printing keys operative on said upright lever, and means extending to 95 the front of the machine for shifting said upright lever laterally to either one of a plurality of predetermined operative positions, said upright lever being also settable in a position where it is ineffective to actuate said operating lever. 100

5. In a typewriting machine, the combination of a ribbon vibrator, an operating lever comprising two arms angularly disposed to each other, one connected to the 105 vibrator and one extending downward, and further comprising two lateral branches which support a pivot pin for the lever, and actuating means co-operative with the downwardly extending arm of said lever. 110

6. In a typewriting machine, the combination of ribbon spools, a ribbon vibrator arranged between said spools, an operating lever, means for actuating said operating lever, and a guiding and supporting device 115 on which said lever is pivoted and by which said vibrator is guided.

7. In a typewriting machine, the combination of ribbon spools, a ribbon vibrator arranged between said spools, an operating 120 lever, means for actuating said operating lever, and a guiding and supporting device on which said lever is pivoted and by which said vibrator is guided and which also provides relatively stationary guides for the 125 ribbon, one of said stationary guides being arranged at each side of the vibrator and between it and one of the ribbon spools.

8. In a typewriting machine, the combination of ribbon spools, a ribbon vibrator, 130

an operating lever, means for actuating said lever, and a bracket on which said lever is pivoted, said bracket supporting a screw which coöperates with a slot formed in said 5 vibrator and also supporting upwardly extending guide fingers which coöperate with the ribbon one between each spool and the ribbon vibrator.

9. In a typewriting machine, the combination of a platen, a shift rail, ribbon spools, a ribbon vibrator, an operating lever, means for actuating said lever, and a bracket fixed to said rail and providing a pivotal support for said lever, a device by 10 which the vibrator is guided during its vibratory movements and providing also a pair of ribbon guiding fingers arranged beyond the sides of the vibrator and independent thereof.

10. In a typewriting machine, the combination of a platen, a shift rail, ribbon spools, a ribbon vibrator, an operating lever, means for actuating said lever, and a sheet-metal bracket detachably fixed to said 15 rail and having under said rail ears on which said lever is pivoted and further carrying forward of said rail a guide screw which coöperates with a slot in the vibrator and also provided with ribbon guide fingers arranged one at each side of said vibrator 20 and extending upward, the portions of the ribbon extending from the vibrator to the spools passing behind said fingers.

11. In a typewriting machine, the combination of a ribbon vibrator, devices for 25 vibrating the same at printing operations, means for shifting said vibrator to change its normal position, and means operating automatically when the vibrator is shifted 30 to shift certain of said devices substantially half the extent to which the vibrator is shifted.

12. In a typewriting machine, the combination of a ribbon vibrator, devices for 35 vibrating the same at printing operations including a lever, means for shifting said vibrator to change its normal position, and means operating automatically when the vibrator is shifted to differentially shift said 40 lever.

13. In a typewriting machine, the combination of a ribbon vibrator, devices for 45 vibrating the same at printing operations including a lever, and means for shifting said vibrator to change its normal position, said means operating automatically when the vibrator is shifted to shift said lever half as far.

14. In a typewriting machine, the combination of a shiftable ribbon vibrator, a non-shiftable actuating device, and an intermediate device for transmitting motion from 50 said actuating device to said vibrator, said intermediate device being shiftable to a different extent from the vibrator.

15. In a typewriting machine, the combination of a shiftable ribbon vibrator, a non-shiftable actuating device, and an intermediate device for transmitting motion from 55 said actuating device to said vibrator, said intermediate device being shiftable only half the extent to which the vibrator is shifted.

16. In a typewriting machine, the combination of a ribbon vibrator, a key operated 60 actuating device, an intermediate device for transmitting motion from said first named device to said vibrator, means for shifting said vibrator, and means operating simultaneously to differentially shift said intermediate device.

17. In a typewriting machine, the combination of a ribbon vibrator, a key operated 65 actuating device, an intermediate device for transmitting motion from said first named device to said vibrator, case shifting mechanism, and means for automatically shifting said vibrator when said case shifting mechanism is operated and for simultaneously shifting said intermediate device to a different 70 extent.

18. In a typewriting machine, the combination of a ribbon vibrator, an operating lever, a key controlled actuating device engageable with said lever, and means for 75 effecting differential shifting movements of said lever and said actuating device.

19. In a typewriting machine, the combination of case shifting mechanism, a ribbon vibrator, an operating lever, a key controlled actuating device engageable with said lever, and means for effecting differential shifting movements of said lever and said 80 actuating device, said means operating automatically when the case shifting operation 100 takes place.

20. In a typewriting machine, the combination of case shifting mechanism including a shiftable frame, a ribbon vibrator connected to shift with said frame, means including an actuating device for vibrating 105 said vibrator, a support for said device, and a pair of links on which said support is mounted, one end of each link having a stationary pivot and the other end being pivoted 110 on said shiftable frame.

21. In a typewriting machine, the combination of a case shifting mechanism including a shiftable frame, a ribbon vibrator connected to shift with said frame, means including an actuating device for vibrating 115 said vibrator, a support for said device, and a pair of links one end of each link being pivotally connected to said shiftable frame and the other end having a stationary pivot, 120 said support being pivotally connected to each link at a point substantially equidistant from its pivoted ends.

22. In a typewriting machine, the combination of case shifting mechanism including 125

- 5 a shiftable frame, a ribbon vibrator connected to shift with said frame, means including a lever of the first order for vibrating said vibrator, a bracket on which said lever is fulcrumed, and a pair of links, one end of each link being pivoted on said shiftable frame and the other link having a stationary pivot, said bracket having a pivotal connection with each link between its pivots.
- 10 23. In a typewriting machine, the combination of case shifting mechanism including a shiftable frame, a ribbon vibrator connected to shift with said frame, means including a lever of the first order for vibrating said vibrator, a bracket on which said lever is fulcrumed, and a pair of links, one end of each link being pivoted on said shiftable frame and the other link having a stationary pivot, said bracket being pivotally supported on said links, and means for setting and resetting said bracket and said lever independently of shifting movements of said links.
- 15 24. In a typewriting machine, the combination of a shiftable platen, a shiftable ribbon vibrator, an actuating device for said vibrator differentially shiftable when said vibrator is shifted, and means for setting and resetting said device independently of shifting movements of said vibrator to vary the throw of the vibrator.
- 20 25. In a typewriting machine, the combination of a ribbon vibrator, an operating lever, an upright sub-lever of the first order contactive at its upper end with said operating lever and provided at its lower end with steps or operating faces one in a plane behind the other, a key operated rock shaft provided with a projection for coöperation with said steps, and means for shifting said sub-lever laterally to bring said steps in alternation opposite said projection on the rock shaft.
- 25 26. In a typewriting machine, the combination of a ribbon vibrator, an operating lever, an upright sub-lever of the first order contactive at its upper end with said operating lever and provided at its lower end with steps or operating faces one in a plane behind the other, a key operated rock shaft provided with a projection for coöperation with said steps, a slidable support on which said sub-lever is pivoted, and means extending to the front of the machine for sliding said support laterally back and forth at will to bring said steps in alternation opposite to said projection.
- 30 27. In a typewriting machine, the combination of a ribbon vibrator, an operating lever, an upright sub-lever of the first order contactive at its upper end with said operating lever and provided at its lower end with steps or operating faces one in a plane behind the other, a key operated device coöperating with said steps, a slidable support
- 35 in which said sub-lever is pivoted, and means extending to the front of the machine for sliding said support laterally back and forth at will to bring said steps in alternation opposite to said device, 70 said support being further slidable to a position where said coöperating device is inoperative on either step.
- 40 28. In a typewriting machine, the combination of a ribbon vibrator, an operating lever, an upright sub-lever of the first order contactive at its upper end with said operating lever and provided at its lower end with steps or operating faces one in a plane behind the other, a key operated device coöperating with said steps, a bracket on which said sub-lever is pivoted, a shift frame, links connected to said shift frame and having pin and slot connections with said bracket, and means extending to the front of the machine for sliding said bracket and said sub-lever laterally independently of said shift frame.
- 45 29. In a typewriting machine, the combination of a ribbon vibrator, an operating lever, an upright sub-lever of the first order contactive at its upper end with said operating lever and provided at its lower end with steps or operating faces one in a plane behind the other, a slidable bracket 95 on which said sub-lever is pivoted, a key operated rock shaft provided with a projection for coöperation with said steps, and means for shifting said bracket laterally to bring said steps in alternation opposite said 100 projection on the rock shaft, said means comprising a rock shaft extending to the front of the machine and provided with a finger button, a crank arm on said last named rock shaft, and a link connecting 105 said crank arm with said bracket.
- 50 30. In a typewriting machine, the combination of a platen, a platen shifting frame, a ribbon vibrator, actuating devices therefor including a lever supported on said shifting frame, ribbon stop devices mounted on said shifting frame separately from said lever, and means for variably setting said stop devices and said lever to vary the throw of the 110 vibrator and also its point of arrest.
- 55 31. In a typewriting machine, the combination of a platen, a platen shifting frame, a ribbon vibrator, an operating lever pivotally mounted on said frame, actuating devices including a sub-lever supported on said shifting frame, stop devices for said operating lever also mounted on said frame, and means operative to variably set said stop devices and said sub-lever on said frame.
- 60 32. In a typewriting machine, the combination of a platen, a key controlled platen shifting frame including a cross bar, a ribbon vibrator, an operating lever pivotally mounted on said frame, actuating devices for said lever including a sub-lever support- 115
- 65 120
- 70 125
- 75 130

ing bracket having connections with said bar, a ribbon stop frame slidably mounted on said bar, and means extending to the front of the machine for varying the normal 5 relationships of said bracket and said ribbon stop frame with said bar.

33. In ribbon vibrating mechanism for typewriting machines, the combination of ribbon throw varying means settable also 10 in position to render the printing keys inoperative on the ribbon vibrator, and a stop device for normally positioning the vibrator, said stop device being settable to permit the vibrator to move by gravity farther 15 from the printing point when the printing keys are inoperative on a said vibrator.

34. In a typewriting machine, the combination of a ribbon vibrator, an operating de-

vice, stepped stop arms above and below said device, and means for setting said arms 20 to bring different steps both above and below said device to operative positions.

35. In a typewriting machine, the combination with a ribbon vibrator and mechanism for varying the throw of said vibrator, 25 of variable stop devices for variably limiting both the movement of the vibrator toward the printing point and also its movement away from the printing point.

Signed at Ilion, in the county of Herkimer, and State of New York, this 13th day 30 of January, A. D. 1915.

EDWIN E. BARNEY.
